UNITED STATES PATENT OFFICE.

FRED E. HOLMES, OF DETROIT, MICHIGAN.

LAMP.

1,271,574.

Specification of Letters Patent

Patented July 9, 1918.

Application filed March 26, 1917. Serial No. 157,419.

To all whom it may concern:

Be it known that I, FRED E. HOLMES, a citizen of the United States of America, residing at Detroit, in the county of Wayne 5 and State of Michigan, have invented certain new and useful Improvements in Lamps, of which the following is a specification, reference being had therein to the accompanying drawings.

10 This invention relates to automobile lamps or the like and refers more particularly to a new and improved construction adapted for use as a headlight or the like.

15 Among the objects of the invention are to provide means whereby the rays of the light can be thrown downward or to other positions different from the normal; to utilize the shifting of the reflector and the bulb or other source of light for this purpose; to 20 provide electrical-controlled means for automatically shifting the reflector or otherwise throwing the light out of its normal path and more particularly to provide electrical-controlled means whereby when the 25 circuit is closed the reflector will be positively shifted in one direction and will remain in this position until the circuit is again closed; to so construct and arrange the parts that upon the next closing of the 30 circuit the reflector will be automatically shifted to its normal position, thus avoiding the necessity of maintaining the closed circuit to hold the reflector in either position of adjustment.

35 The invention also resides in the particular construction of the shifting mechanism and in such further details of construction as will more fully hereinafter appear.

In the drawings:

40 Figure 1 is a horizontal sectional view through a lamp embodying my invention; Fig. 2 is a vertical sectional view through the construction shown in Fig. 1;

45 Fig. 3 is an enlarged side elevational view partly in section of the shifting assembly;

Fig. 4 is an enlarged side elevational view of the shifting assembly, at right angles to Fig. 3.

50 Describing in detail the construction shown in the drawings, A designates the lamp casing, B the electric light bulb and C the reflector in which the bulb is mounted to move with the reflector. The opposite sides of the reflector are provided with projecting pins D and D' which extend into 55 bearings E and E' on the inner face of the

casing A and form an axial pivot about which the reflector C may be rocked from the normal position shown in full lines in Fig. 2 to the position shown in dotted lines in this figure.

For rocking the reflector to its various positions there is employed a rock arm or rod F having one end pivoted at F' to a lever G fixed to the pin D'. The other end 65 of the arm F is pivotally connected at F² to a lever G' keyed to the shaft H, the connection being such that as the shaft H is rocked, it will through the action of the lever G', the rod F and the lever G, produce a corresponding rotation of the pin D' and thus 70 rock the reflector about its axis.

While various constructions could be employed for rocking the shaft H, I preferably utilize an electrical-controlled mechanism, the detailed construction and operation of which is as follows:

Secured to the shaft H is a pin I having its ends I² extending into slots J' and J² in the yoke member J. The yoke member J in 80 turn is secured by rivets J⁵ or other suitable means to the movable plunger K of the electro-magnet. The current to the coils L of the magnet for energizing the stationary magnet L' is controlled by a switch L² 85 in the circuit L³. The arrangement is such that the closing of the circuit through the switch will energize the electro-magnet, draw the plunger down and rock the reflector, and I have provided novel means whereby the temporary closing of the circuit through the switch will at one time shift the reflector from its normal position and the next closing of the circuit will electrically shift it back to initial position.

95 In detail the mechanism for accomplishing this result comprises a throw-over device constructed and arranged as follows: Loosely sleeved on the shaft H is a yoke M, to the outer end of which there is pivoted 100 at M' an arm N, the latter at its rear end being secured to the casing through a spring N'. Keyed or otherwise fixedly secured to the shaft H inside of the yoke portion is an arm O which carries a transverse pin O', the ends of which project into elongated slots Q in the yoke member M. This slot and pin arrangement permits of sufficient lost motion to provide a throw-over mechanism whereby the arm O can be thrown 105 over center bringing the pivoted end M' of the arm N down below the shaft H so that 110

in its position, as shown in Fig. 2, the spring N' will serve to hold the arm O and shaft H in the position shown in Fig. 2.

However upon the closing of the circuit 5 the plunger K will be drawn downward carrying with it the yoke J, which acting upon the pin I, will rock the shaft H so as to carry the pivoted end M' below the plane of the shaft H and allow the spring to hold 10 the device in the position shown in Fig. 3. Upon the next closing of the switch the plunger K being drawn downward will act upon the opposite end of the pin I and rock the shaft H in the reverse direction. In 15 each case the pin and slot engagement O' and Q will cause the arm to throw-over center and thus hold the reflector in either position of adjustment until the circuit is again closed. This novel arrangement of 20 parts avoids the necessity of keeping the circuit closed in order to hold the reflector in its adjusted position. The magnet must be strong enough to overcome the tension of the spring N', which spring also serves 25 to hold the reflector in either of its positions.

It will be noted that the bulb B is shifted with the reflector C, there being sufficient play permitted of the leading in wires R 30 and R' from the socket R² so as not to in-

terfere with the movement of the reflector. Various changes in the particular construction and arrangement of parts can be made without departing from the scope of my invention.

35

What I claim as my invention is:

1. The combination with a casing, of a reflector pivotally mounted in the casing, a rock arm for rocking said reflector about its pivot, electrical-controlled means for 40 positively actuating said rock arm in either direction, and a spring for holding the mechanism in either of its positions of adjustment.

2. The combination with a casing, of a 45 reflector movably mounted in the casing, a single magnet for the movable member also mounted in said casing, connecting mechanism between the reflector and the movable member of the magnet arranged to positively and automatically move the reflector in one direction upon closing of the circuit to the magnet and to positively and automatically move the reflector in the opposite direction upon the next closing of the circuit to the magnet, and a spring for holding the mechanism in either of its positions of 50 adjustment.

In testimony whereof I affix my signature.

FRED E. HOLMES.
